RADIATOR VALVE

James R. Lawler, Glencoe, Ill., assignor, by mesne assignments, to Lawler Automatic Controls, Inc., Mount Vernon, N. Y., a corporation of New York

Application May 19, 1931. Serial No. 538,526

5 Claims. (Cl. 236—42)

This invention relates to valves in general and particularly to thermostatically controlled radiator valves.

The primary object of the invention is to provide a sensitive positively operating radiator valve which is applied inside of a radiator, which can be readily and economically manufactured, and which is applicable for application in the usual opening provided in radiators and which is usually closed by a plug.

Numerous other objects and advantages will be apparent throughout the progress of the following specification.

The accompanying drawing illustrates a selected embodiment of the invention and the views therein are as follows:

Fig. 1 is a detail elevation of a radiator having the improved valve applied thereto.

Fig. 2 is a detail sectional view showing the valve applied to a radiator and having the thermostatic control operatively connected therewith.

Fig. 3 is a detail end elevation of the valve.

Fig. 4 is a sectional view of an improved form 25 of valve.

Fig. 5 is a detail sectional view showing another manner in which the valve may be applied to a radiator.

Referring to the drawing, 1 designates a radiator having the usual threaded opening 2 which is usually closed by a plug (not shown). The opening 2 is the opening which is usually provided in radiators to permit the core to be removed during the process of casting and may be located either at the upper or the lower end of the radiator. The radiator is, of course, provided with an outlet (not shown) to which the return line is connected. A supply line 3 containing a heating fluid of steam or hot water leads to the improved valve 4. If desired, a hand controlled valve 5 may be interposed between the supply line 3 and improved valve 4.

The new valve 4 comprises a body portion 6 which threadedly engages the opening 2, and the supporting member 7 which is connected to the body portion 6 by means of fastening elements 8. The body portion 6 constitutes a threaded bushing and has an elongated end housing 8 which is hollow to provide a chamber 9. A passage 10 is formed in the body 6, as clearly shown in Fig. 2, and has communication with the chamber 9. A corrugated, collapsible, and expansible member or bellows 11 is arranged in the chamber 9 and has a rigid portion 12 rigidly connected to the bellows. A screw 13 passes through

the member 12 and makes threaded engagement with a solid plug or stem 14. A spring 15 surrounds the screw 13 to provide a resilient connection between the member 12 and the member 14 and to take up play between the two members. 60

This construction also provides a flexible connection between the members, and acts as a relief spring when the valve has already moved to its limit. The spring provides an additional movement which might take place if the thermostat were overheated. This relief spring is ex-

tremely important in valves of the present type as extremely high temperatures might develop which would fracture some part of the tubing if this relief means were not provided. This plug 70

has a flange 16 provided thereon which is beveled at 17 and makes a tight fit with the bevel portion 18 of the housing. A threaded bushing 19 is arranged inside of the body 6 and has an angular opening 20 through which the solid stem 14 extends. A valve 21 is connected to the solid

plug or stem by means of a screw 22 and is adapted to bear against the valve seat 23 to shut off communication from the supply line 3. 75

An automatic regulating control or thermostat 24 is provided with a pipe 25 which communicates with the passage 10. The thermostat comprises a casing 26 which is fixed to a plug or nipple 27, as indicated at 28. A nut 29 has

threaded engagement with the plug or nipple 27 85 and locks the casing 26 rigidly to the nipple 27. A collapsible, metal bellows 30 is arranged inside of the thermostatic element 24 and contains a metal plug or stem 31. This stem extends through the nipple 27, has threaded engagement 90

therewith and is provided with a serrated thumb nut 32 for the purpose of regulating the metal bellows 30. 95

The automatic control or thermostat 24 is filled with an expansible fluid 33. The fluid in the thermostat 24 expands under heat, causing the fluid to flow through the pipe 25 into the passage 10 to fill the chamber 9. When sufficient fluid passes into the chamber 9, a pressure exists in the chamber causing the bellows to collapse and move the valve 21 against its seat 23 and thereby shut off communication from the supply line 3. 100

When the temperature of the thermostatic element reaches a certain predetermined low temperature, the fluid will contract and flow out of the chamber and back into the thermostat, thus permitting the metal bellows to attain its normal position and move the valve 21 from its seat 23. 105

Normally, however, the resiliency of the bellows 11 is sufficient to retract the valve from its seat. 110

but it may be desirable to arrange a spring 34, Fig. 4, between the seat 23 and the valve 21 for pushing the valve back away from the seat when the fluid leaves the chamber 9.

5 The valve 4, as shown in Fig. 2, extends into the body of the radiator, the body portion being provided with spaced legs 35 providing spaces or openings 36 therebetween for permitting the heating fluid coming through the line 3 to pass through the openings 36 and into the radiator. The valve being in direct communication with the heating fluid, will attain a temperature substantially the same as the heating fluid. Therefore, the valve is normally set to meet these conditions, 10 there being a greater difference in temperature between the fluid in the thermostat than the temperature of the fluid in the supply line. The valve, however, and the thermostat are set to overcome these variations in temperature. In 15 other words, the operation of the valve is controlled by the temperature of the fluid in the thermostat 24.

The stem 31 and its cooperating thumb nut 32 is used for the purpose of expanding or contracting the bellows 30. If a higher temperature is required, the thumb nut 32 is operated to contract the bellows. Thus, the fluid in the thermostat must reach a higher temperature in order 20 to expand sufficiently to operate the valve member 21. Also, when a lower temperature is desired, the thumb nut 32 is operated in a reverse direction to expand the bellows 30. As soon as 25 the liquid in the thermostat expands, it will immediately enter the chamber 9, operate the bellows 11 and close the valve member 21. The valve just described has its body threaded for direct engagement with the threaded opening 2 in the radiator. However, it is often desirable 30 that the entire valve be not rotated and in such instance the valve will merely slip into the opening as shown in Fig. 5, there being a separate bushing 37 which threadedly engages the opening 2. This bushing has threaded engagement 35 with a packing nut 38, a backing gland or rubber 40 being arranged between the two members as shown in Fig. 5 for making a tight connection between the valve body and the bushing 37.

In operation, the valve is arranged in place 45 and projecting into the radiator. The thermostat element is arranged in some predetermined position, such as on the front, where the temperature is usually the lowest. Thus, when the 50 temperature of the atmosphere surrounding the thermostat reaches a predetermined minimum 55 temperature, the fluid in the chamber 9 will flow into the thermostat permitting the valve member 21 to become unseated and permitting the heating fluid coming through the supply line 3, to enter the radiator. When the temperature of 60 the atmosphere surrounding the thermostat reaches a certain predetermined maximum, the fluid in the thermostat will expand and flow through the line 25, through the passage 10 and into the chamber 9 where the pressure of the 65 fluid will cause contraction of the metal bellows 11 and move the valve member 21 against its seat 23 and cut off communication from the supply line 3.

The invention provides a valve which extends 70 into the body of the radiator and does not extend out into the room as in the case with conventional valves. The improved valve may be applied to existing radiators without the necessity of providing special radiators for accommodating the valve. The valve of the present type is

particularly applicable for old radiators now in use which are not equipped with thermostatically controlled valves. The valve is simple in construction, efficient and positive in operation, can be quickly and easily installed, and may be readily and economically manufactured.

Changes may be made in the form, construction, and arrangement of the parts without departing from the spirit of the invention or sacrificing any of its advantages, and the right is hereby reserved to make all such changes as fairly fall within the scope of the following claims.

The invention is hereby claimed as follows:

1. A valve having a body and adapted to be fastened to a radiator, said body extending into the interior of the radiator, a valve carried by said body and totally housed within the radiator, means remotely situated from the valve and controlled by atmospheric temperature for operating said valve, and means passing through the said body into the inside of the radiator and operatively connected to said first named means for establishing communication from the first named means to the said valve.

2. In a radiator, a valve totally arranged inside of said radiator, a body for said valve and extending into the interior of the radiator, said body having openings therein to permit heating fluid to pass therethrough, a member inside of the radiator and body and adapted to be expanded and collapsed to operate the valve, a thermostat outside of the radiator and carrying thermal fluid which is expansible and contractible due to higher and lower temperatures respectively, said thermostat being operatively connected to said body, and means including the body leading to the member to cause contraction of said member to close the valve when the fluid in the thermostat reaches a predetermined high temperature and permitting expansion of said member when the temperature of the fluid reaches a predetermined minimum.

3. In a thermostatically controlled radiator valve, a valve body inside of the radiator and having exterior threads for threaded engagement with the radiator, a valve arranged in said body, fluid pressure operated means for operating said valve, a receptacle containing thermal fluid remotely situated from said valve and having a passage through the body portion and leading to the interior of the radiator for controlling the operation of the thermostatic control means, a bellows arranged in said container, and a threaded stem arranged inside of said bellows for varying the pressure of the fluid in said container.

4. In a radiator controlling valve, a valve casing arranged inside of a radiator and having exterior threads for threaded engagement with a threaded opening in a radiator, said casing having a main body portion and an off-set body portion of smaller diameter than the main body portion, both of said portions being integrally connected by spaced legs, a fluid inlet line connected to the main body portion, the heating fluid entering the radiator through the spaces between the legs, a valve seat in said main body portion, a valve operable against said seat, a valve stem in the off-set portion, a bellows surrounding the stem and arranged in the off-set body, a container containing thermal liquid for controlling the bellows, a liquid line from the container and connected to the casing, said casing having a longitudinal passage in the walls thereof and establishing

communication with the interior of the off-set body portion.

5. In a radiator controlling valve, a valve casing arranged inside of a radiator and having exterior threads for threaded engagement with a threaded opening in a radiator, said casing having a main body portion and an off-set body portion of smaller diameter than the main body portion, both of said portions being integrally connected by spaced legs, a fluid inlet line connected to the main body portion, the heating fluid entering the radiator through the spaces between the legs, a valve seat in said main body portion, a valve operable against said seat, a

valve stem in the off-set portion, a bushing threadedly engaging the inside walls of the main body portion and through which the valve stem extends, said bushing supporting the valve stem and providing an abutment for the bellows, a 80 bellows surrounding the stem and arranged in the off-set body, a container containing thermal liquid for controlling the bellows, a liquid line from the container and connected to the casing, said casing having a longitudinal passage in the walls thereof and establishing communication with the interior of the off-set body portion.
